UNITED STATES PATENT OFFICE

2,583,275

SPINNING TOP

Robert D. Olson, Fort Wayne, Ind.

Application April 5, 1949, Serial No. 85,554

1 Claim. (Cl. 46—49)

1

This invention relates to new and useful improvements in spinning tops and has for its primary object to provide a top having a fixed colored disc and a rotatable colored disc, means being provided for causing a speed differential between the two discs so that while the top is spinning, different colors and color blendings are visible.

A meritorious feature of this invention resides in provision of a conical housing having a transversely disposed fixed partition, the partition being formed with a multi-colored pattern surface, a rotatable multi-colored disc being disposed in the housing and spaced above the partition so that the disc rotates independently of the housing, presenting during the rotation different colors and color blendings.

Another meritorious feature of this invention resides in the provision of means carried by the rotatable disc for selectively varying and changing the speed and manner of rotation of the disc independently of the rotation of the housing so that the disc rotates on its own shaft or spindle and is provided with prearranged patterns of different colors to exhibit a blending and change of colors while spinning.

Another important object of this invention is to provide a novel and practical color change top, which may be inexpensively manufactured and which will be durable and practical in use.

These and ancillary objects and other meritorious features are attained by this invention, preferred embodiments of which are set forth in the following description and illustrated in the accompanying drawings, wherein:

Figure 1 is a vertical sectional view of one embodiment of this invention;

Figure 2 is a vertical sectional view of another embodiment of this invention, and

Figure 3 is a top plan view of the tops shown in Figures 1 and 2.

The body of the top comprises a substantially conical hollow housing 10, having suitably secured at its upper edge or its major end a substantially concavo-convex cover disk 12. The cover disk 12 is preferably transparent, but may be formed with a series of segment shaped apertures or the like, so as to render the interior of the housing 10 viewable from the top.

A disk-like partition member 14 is transparently disposed in the housing and fixed thereto at the juncture point between the housing and the cover, as seen in Figure 1. The upper surface of the partition 14 may be suitably ornamented and inscribed with a multi-color pattern or ornamental configuration.

Of course, if a humming top is desired, the upper part of the housing may be provided with openings 16, which will produce the humming sound while the housing is rotating or spinning.

2

In the latter respect, a spherical spinning point 18 is embedded in and integrally formed with the minor end 20 of the housing.

Centrally upraised from the transparent cover 12 is a head 22 having a vertically disposed centrally positioned aperture 24 therein. A hub 26 having an annular side wall 28 is seated on the head and formed with a centrally disposed passage 30, the same being aligned with the vertical opening 24 for a purpose to be later described. It can be appreciated that the annular side wall 28 is provided so that the top may be spun in the usual manner. In this respect, a conventional flexible operating member, such as a rope or string or the like, is wound or coiled around the side wall and then when the top is disposed in a vertical position resting on the spherical spinning point 18, the operating member is pulled or unwound quickly from the hub.

As the housing rotates, it can be seen that the different colors painted on the upper surface of the partition will be viewed through the transparent cover 12. In order to impart a color blending and to exhibit a changeable blending of colors when the top is spinning, a rotatable disc 32 is disposed in the compartment defined by the partition member 14 and the cover 12. The upper surface of the rotatable disc 32 is suitably covered with a pattern formation of different colors, complementary to the pattern on the upper surface of the partition 14. It can be seen that the outer circumferential edge of the disc 32 is spaced inwardly from the juncture point or guide wall of the cover and housing, so that the upper surface of the partition adjacent the outer edge, is exposed so that the upper surface of the partition, adjacent the edge thereof may be viewed through the cover. A rotatable shaft or spindle 34 has one end centrally disposed in the disc 32 and fixed thereto as at 36. The shaft 34 extends vertically through the aperture 24 and the passage 30 and has its other end peened over as at 38 on the upper outer edge of the hub. Thus, it can be seen that when the housing is rotating, the disc 32 will rotate also but independently of the rotation of the housing and the speed and manner of rotation of the disc may be easily changed by placing an object or exerting a slight pressure on the peened end 38 of the shaft. The slight pressure exerted thereon will temporarily halt or break the rotation of the disc 32 but will not interfere with the rotation of the housing 10.

Another embodiment of this invention is shown in Figure 2, wherein the structure of the top is similar but different means is provided for effecting the change of color or color blending visible through the cover 12. In this respect, the disc 32 is fixed on one end of a rotating shaft 40, the shaft 40 terminating at its other end in a semi-spherical spinning point 42 having a flat spinning

surface 44. The head 26 is carried by a vertical spindle 46, the same being securely disposed in an aperture 48 in the upstanding head 50 of the cover 12. A conventional bearing 52 is disposed at the minor end of the housing 10 to rotatably receive the shaft 40 and to space the spinning point 42 from the minor end of the housing. To effect a positive color changing, when the top is spun, in a manner as disclosed in the foregoing, it can be seen that the surface 44 of the spinning point is subject to friction created between the bearing point and upper surface and a supporting surface on which the top is being spun.

Thus, it can be seen that there is provided a novel top of attractive appearance and design, which is easily and inexpensively provided with an automatic and a manual color changing control.

However, since many other purposes and embodiments of this invention will become apparent to those skilled in the art, it is to be understood that improvements may be effected on the basic design disclosed, the same coming within the spirit of the invention and the scope of the appended claim.

Having described the invention, what is claimed as new is:

A toy top including a conical housing, a transparent concave cover disk seated on the upper edge of said housing, a fixed disk-like partition disposed transversely in the housing at the juncture of the housing and cover disk, said partition being inscribed with a multi-colored pattern, a centrally apertured head on said cover disk, a vertical spindle disposed in said head, a hub having an annular side wall disposed on said spindle, a flat rotatable disk disposed in said housing and spaced above the partition, said

disk having a multi-colored pattern formed on its upper surface and having its circumferential edge spaced inwardly from the side wall of the housing to expose therebeyond the outer edge of the partition, the portion of said cover disk directly overlying said outer edge being transparent, and means carried by said rotatable disk for varying the speed and manner of rotation thereof independently of the rotation of the housing, said housing having an aperture at its minor end and having a bearing therein, said last-named means including a vertical shaft fixed at one end to said disk and rotatably disposed through said partition and bearing, and a semi-spherical tip on said shaft at its outer end with the flat side for spinning frictional contact on the surface supporting the top whereby the relative speed between said disk and said housing is varied.
